[57] CLAIM

The ornamental design for a electrical control panel for
mobile storage units, as shown.

DESCRIPTION

FIG. 1 is a front and upper right isometric view of an
electrical control panel for mobile storage units showing
our new design;

FIG. 2 is a front elevational view thereof;

FIG. 3 is a top plan view thereof;

FIG. 4 is a right side elevational view thereof;

FIG. 5 is a back elevational view thereof;

FIG. 6 is a left side elevational view thereof; and,

FIG. 7 is a bottom plan view thereof.
